(57) **CLAIM**

The ornamental design for a non-contact type data carrier, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a rear elevational view of a first embodiment of a non-contact type data carrier showing my new design;

FIG. 2 is a right side elevational view thereof;

FIG. 3 is a top plan view thereof.

FIG. 4 is a rear elevational view of a second embodiment of a non-contact type data carrier showing my new design;

FIG. 5 is a right side elevational view thereof; and,

FIG. 6 is a top plan view thereof.

The even-dash broken lines showing of unclaimed portions of the non-contact type data carrier form no part of the claimed design. The dot-dash broken lines define the boundaries of, but not included in, the claimed design.

All surfaces not shown form no part of the claimed design.
